TYPE-CLAMPING ATTACHMENT FOR CHASES

Application filed October 4, 1928. Serial No. 310,345.

This invention relates to type printing accessories, and has particular reference to an improvement in a type clamping attachment for a chase which is applicable to chases of either the inside or outside forms.

Up to the present time, the type on the inside chases have been locked up from the ends by the usual quoins and from the sides by screws directly threaded through one of the side rails for engaging a bearing strip, while in the outside chases quoins are employed to lock up the type from one end and from one side. Obviously, these methods of locking the type in the chase subject the side rails especially to localized strains and pressures which tend to buckle, warp or otherwise distort the chase to such an extent that after a very limited time, the same is rendered unfit for further use and must be discarded.

20 In order to overcome the above recited objections and disadvantages, the present invention broadly comprehends means applicable to the side of a chase for relieving the side rail of strains, stresses or other pressures thereon incident to the locking of the type in the chase whereby distortion of the chase is precluded and the strains and stresses are transmitted directly to the means employed so that said means may be economically re-
30 placed when necessary.

More specifically, the invention comprehends a means of the character described and for the purpose set forth which is in the nature of a bar detachably connected at its 35 opposite ends to the side of the chase with elements threaded through said bar for clampingly engaging the type to transmit the strains and stresses to said bar without subjecting the chase rail to any distorting action.

40 Other objects of the invention reside in the simplicity of construction of the type clamping attachment and the mode of use of the same, the economy with which the same may be produced and the general efficiency derived therefrom.

With the above recited and other objects in view, reference is had to the following description and accompanying drawings, in 50 which there is exhibited one example or em-

bodiment of the invention, while the claims define the actual scope of the same.

In the drawings:

Figure 1 is a plan view of a chase of the inside type equipped with a clamping attachment constructed in accordance with the invention. 55

Figure 2 is a fragmentary enlarged view thereof illustrating the type clamping attachment in active use. 60

Figure 3 is a side view thereof.

Figure 4 is a face view of the bar of the type clamping attachment removed.

Figure 5 is a plan view of the type clamping attachment as applied to a chase of the outside form. 65

Referring to the drawings by characters of reference, and more particularly to Figures 1 to 4, inclusive, 10 designates a chase of the inside from which is provided with end rails 70 11 and 12 and side rails 13 and 14. The side rail 13 is provided with a plurality of longitudinally spaced apertures 15. A bar 16 is detachably associated with the side rail 13 by any suitable means, such as headed screws 75 17, the threaded shanks of which extend through slots 18 in the bar 16 and are anchored in threaded apertures 19 in the chase. The screws may be of the usual type in which the heads are provided with non-circular 80 sockets 20 for the reception of wrenches for manipulating the same. The bar 16 is provided with threaded apertures 21 longitudinally spaced to approximately coincide with the apertures 15 in the side rail 13 of the 85 chase. Screws 22 engage through the threaded apertures 21 and are designed to loosely extend through the apertures 15 in the side rail 13 of the chase for engagement or impingement of their inner ends against 90 a bearing strip 23 disposed alongside of the composed type A and arranged within the chase and locked up from the end by the usual furniture B and quoins C. It thus follows that the strain of clamping or locking up the 95 composed type from the side of the chase is transmitted directly to the bar 16 without affecting in any way the side rail 13 of the chase. When the chase with the type is deposited onto the bed of the press, the 100

intermediate chases may have the bars removed therefrom by unscrewing the screws 17. It is obvious that the endmost chases may be locked up on the bed of the press without removing the bar 16 therefrom. 5 When the bar 16 has been warped or distorted in one direction by its continual use, the same may be placed on the chase in a reverse direction to obtain additional 10 use therefrom. If the bar is broken or distorted to such an extent as to preclude its further use, it may be replaced at small expense. It will thus be seen that a type clamping attachment has been devised which 15 materially increases the length of life and usefulness of a chase, which attachment is economical and efficient in its purpose.

In an outside form of chase, as illustrated in Figure 5, the type clamping attachment is 20 shown as applied thereto for the purpose of relieving the side rail 25 of localized strains due to the locking up of the composition D from the side by the usual quoins E. In this instance, the attachment is of the same construction and functions in the same manner 25 as that described for the inside form of chase, with the exception that the screws 22 are initially threaded inwardly to space the strip 23 from the side rail of the frame a pre- 30 determined distance prior to locking up the composition from the opposite side with the quoins E. Obviously, in this form, the bar 16 takes the strain from the clamping action 35 of the quoins E.

35 What is claimed is:

1. In a type clamping attachment for a chase, means carried by the chase adjacent the side rail which is usually subjected to the warping strains, for relieving the same of 40 said strains, said means comprising a bar attached at its opposite ends to one side of the chase and elements threaded through said bar and clampingly engaging the type.

2. In a type clamping attachment for a 45 chase, means carried by the chase adjacent the side rail which is usually subjected to the warping strains, for relieving the same of said strains, said means including a bar attached at its opposite ends to said side of the chase and elements threaded through said 50 bar and freely extending through said side rail for clampingly engaging the type.

3. In a type clamping attachment for a 55 chase, means carried by the chase adjacent the side rail which is usually subjected to the warping strains, for relieving the same of said strains, said means including a bar attached at its opposite ends to said side of the chase and elements threaded through said 60 bar and freely extending through said side rail for clampingly engaging the type and means for detachably securing the bar to the chase whereby the same may be removed after the chase has been positioned on the bed of the 65 press.

4. A chase having an apertured side rail, a 70 bar secured at its opposite ends in flat contact with the side of the chase, elements threaded through the bar and freely extending through the apertured side rail for clampingly engaging the type to relieve said side rail of warping strains.

5. A chase having an apertured side rail, a 75 bar detachably secured at its opposite ends in flat contact with the side of the chase, elements threaded through the bar and freely extending through the apertured side rail for clampingly engaging the type to relieve said side rail of warping strains.

6. The combination with a chase having 80 an apertured side rail, of a type clamping attachment therefor including a member carried by the chase independently of said side rail and means threaded therethrough and freely projecting through the side rail apertures for contact with the type to relieve the side rail of strains.

7. The combination with a chase having an 85 apertured side rail, of a type clamping attachment therefor including a member carried by the chase independently of said side rail and adjustable means carried by said member and extending through the side rail apertures for contact with the type to relieve 90 said apertured side rail of warping strains. 95
